UNITED STATES PATENT OFFICE.

FERDINANDO G. SALERNO, OF CHICAGO, ILLINOIS.

MACHINE FOR APPLYING TOP COATINGS OF COMMINUTED MATERIALS TO CONFECTION-COATED WAFERS.

Application filed May 16, 1923. Serial No. 639,283.

My invention relates to a machine designed to apply a top coating of shredded, granular or other comminuted material upon cakes or wafers to which a coating of some confection of a plastic adhesive material, such as jelly icing, chocolate paste, etc., has been applied by a machine arranged to supply the cakes thus preliminarily coated to the machine constituting my present invention. In Letters Patent No. 1,514,345, granted to me on November 4, 1924, I have described a machine intended and adapted to accomplish the same general purposes as the present machine, and the construction of which is in many respects similar, and the object of my present invention is the production of a new and improved machine, having several desirable features not found in my former machine. One novel feature of my improved machine relates to a more simple arrangement of parts for returning surplus material passing through the distributing screen and between the cakes to the elevator which lifts it and returns it to the supply hopper; another relates to means for directing the blast of wind discharged from the blower apparatus towards the coated wafers, and another to means for regulating the supply of material delivered to the vibrating distributing screen. Other novel and advantageous features of construction incidental to the foregoing and designed to facilitate accomplishment of the ends in view will be apparent from the description of the machine hereinafter given, the essential elements of my invention being more particularly pointed out in the appended claims.

Figure 1 of the accompanying drawings is a side elevation of my improved topping machine, certain parts being broken away to show the construction of parts beyond; Fig. 2 is a plan view of the machine, certain parts being broken away to show parts underneath; Fig. 3 is a fragmentary central longitudinal section through the upper part of the machine, on a larger scale than Fig. 1; Fig. 4 is a transverse vertical section of the machine on the line 4—4 of Fig. 2; Fig. 5 is a cross section through the jet member; and Fig. 6 is an end view of the hopper.

The same reference characters indicate the same parts in all the figures of the drawing.

It may first be explained that the cakes

or wafers to be treated, freshly coated with jelly or other confection, are deposited in successive rows upon the receiving belt of my topping machine, and are thence delivered to a wire-mesh conveyor belt by means of which they are carried first underneath a vibrating screen mechanism for depositing on them the comminuted material and thence past a blower mechanism for imbedding the adherent particles and removing the non-adherent surplus material, after which the coated cakes, by a succession of belts are delivered onto trays for removal and packing.

Proceeding now to a more detailed description of the construction of my machine, the receiving belt A is engaged by the cross-member of a pivoted frame 1, and passes around the small idler rollers 2 and 3 and driving roller 4. From the receiving belt 70 the cakes pass to the endless wire-mesh conveyor belt B which engages the small rollers 5, 6 and 7 and the relatively large driving roller 8. Passing from the conveyor belt, 75 the cakes are delivered to a transfer belt C 80 which engages a small roller 9, a trifle lower than the roller 6, a driving roller 9^a, a small idler roller 9^b, and the rounded nose of a cross-bar forming the cross-member of a swinging frame which is provided with 85 means for adjustment to take up slack in the belt, and also provided with means for raising the outer end or loop of the belt more or less. In the regular operation of the machine the coated cakes are delivered by 90 the transfer belt to trays which are placed on a delivery belt D and removed therefrom by attendants of the machine.

The mechanism for distributing the shredded material on the coated cakes as they 95 pass through the machine, includes a supply hopper 10 within which, adjacent the bottom, is arranged a rotating spiral distributing blade 11 which in the present instance does not extend quite to the ends of the 100 hopper, and the shaft of which is journaled in bearings in the end plates of the hopper box. The passage of material downwardly out of the hopper is controlled by two longitudinally grooved feed rollers 13 and 14 having journals which are pivotally mounted in the lower ends of two pairs of depending arms, marked respectively 13^a and 14^a. As shown in Fig. 3 of the drawing the grooves of the two rollers are off-set angularly so 110

that they do not come in registration as the rollers revolve in such direction that their proximate faces move downwardly.

The arms 13^a are pinned to the end of the 5 hopper so that the roller 13 is in effect mounted in stationary bearings, while the arms 14^a are free to swing on their pivots. At each end of the hopper the arms 13^a and 14^a are adjustably connected by screw bolts, marked 13^b, springs 18^a and 14^c being employed to stress the arms 14^a and roller 14 carried thereby away from the arms 13^a and roller 13.

Below the feed rollers is arranged a 15 movable vibrating screen 15, set in a frame 15^a pivotally hung upon a front pair of rock arms 16 secured to a rock shaft 17 journaled in bearings carried by opposite sides of the machine frame, and a rear pair 20 of rock arms 18 fixed to a rock shaft 18^a similarly mounted. By means of a crank arm 19 fixed to the rock shaft 18^a and operated by a pitman 20 the screen is vibrated to sprinkle material flowing from between 25 the feed rollers over the rows of cakes E passing beneath on the wire mesh conveyor belt. Interchangeable screens of different sizes of mesh are provided, to adapt the machine for distributing different kinds of 30 material.

The surplus material which passes through the meshed conveyor is directed by the inclined sides 21 and 22 of a collecting hopper to a transverse conveyor trough 23 in which 35 is arranged a spiral conveyor 24 which transfers the material to the lower end of a bucket elevator 25 arranged at the side of the machine. The specific construction of the elevator is immaterial and it will suffice to say 40 that it includes an endless sprocket chain 26 passing around a lower sprocket wheel mounted on the shaft of the conveyor 24, and an idler upper sprocket wheel, the chain being equipped with buckets 29 arranged to lift 45 the material and discharge it into a return chute 30 which empties into the supply hopper, adjacent the inner or receiving end of the spiral distributing blade.

A blower mechanism is provided consisting of a fan blower 31 of proper capacity 50 arranged to force a blast of air through a pipe 32 into the top of a cross blower box 33 which is provided with an adjustable jet opening at its bottom by means of a longitudinally-slotted cylindrical jet member 34 55 rotatably mounted in the lower side of the blower box and provided with an operating handle 35 by means of which the direction of the jet of air may be angularly adjusted.

The machine may be driven by any suitable power and various suitable connections 60 for actuating the different moving parts. In the drawings I have illustrated suitable actuating means consisting of an electric motor 36 which is geared to a commercially

well-known variable-speed power-transmitting device known as the Reeves variable-speed transmission and having a pulley 37 arranged to drive the blower through a belt 38, and also having a pulley 39 eccentrically 70 connected to the pitman 20 before mentioned to cause reciprocation of the vibrating screen.

The driving drum of the delivery belt D before mentioned is driven through a gear 75 wheel 70 on the same shaft as the pulley 39, gear wheels 71 and 44 on the shaft 41, a gear wheel 45 on a shaft 46 meshing with the gear wheel 44 and a sprocket chain 47 engaging a sprocket wheel on the shaft 46 and 80 a sprocket wheel 73 on the shaft 48 carrying the drum.

The driving roller of the receiving belt A is equipped with a sprocket wheel 74 which meshes with a sprocket wheel 75 on the shaft 85 48 of the belt A, and is also equipped with a gear wheel 50 which in turn meshes with a gear 51 on the shaft 52 of the driving roller 8 which engages the wire-mesh conveyor belt B before mentioned. 90

The transfer belt C is driven through a sprocket chain 54 engaging a sprocket wheel on the shaft 52 and a sprocket wheel fixed to the shaft 55 which carries the driving roller 9^a. The shaft carrying the small 95 roller 9 carries also a pinion 56 which through an intermediate pinion 56^a is geared to a pinion 57 on the shaft which carries the roller 6, so that the wire-mesh conveyor belt is driven from both ends, a sprocket chain 100 58 being arranged to positively drive the group of pinions 56, 56^a and 57. It will be noted that the adjacent rollers 6 and 9 of the conveyor belt and transfer belt, respectively, are both positively driven, in consequence of which they may be made very small, so that the gap between their top reaches is of small dimensions, without producing the wear and drag upon the belts which would occur were they not thus 105 driven. 110

The two feed rollers 13 and 14 are driven from a sprocket wheel on the shaft 52 by a sprocket chain 59 arranged to engage a sprocket wheel fixed to the shaft of the 115 roller 13, the shafts of the rollers being geared together by intermeshing pinions having teeth sufficiently deep to remain in engagement throughout the range of adjustment of the rollers. 120

The spiral distributing blade 11 is rotated by means of a sprocket chain 60 engaging a sprocket wheel 61 on the shaft of the feed roller 13 and a sprocket wheel 62 on the shaft of the blade 11. 125

The spiral conveyor 24 and the sprocket chain of the elevator are driven by a sprocket chain 40 engaging a sprocket wheel on the shaft 52 and also a sprocket wheel 76 130 rotatably mounted in the frame of the ma-

chine; a second sprocket wheel 77 mounted on the same shaft, and a sprocket chain 78 engaging a sprocket wheel on the same shaft as the conveyor and the lower elevator 5 sprocket wheel to which the buckets are secured.

The adjustment of feed rollers and blower nozzle above described, in connection with the provision of the spiral distributing 10 blade in the supply hopper, enables the machine to be easily and accurately adjusted so that it may be operated to distribute different kinds of comminuted materials upon coated cakes, varying in weight and size, as 15 for instance light, bulky, materials, like shredded cocoanut, or materials consisting of dense, solid particles, like granulated sugar, as well as grated or granular particles of nuts, or other material of still different 20 character. When the direction of the air jet is more nearly perpendicular to the surface of the coated wafers acted upon, its effect is to imbed the particles of coating material into the plastic material of the 25 wafers, while a jet in widely oblique direction has a greater tendency to dislodge surplus, unadherent material. The nozzle can therefore be adjusted to operate in such manner as the nature of material may require to attain the best results.

I claim:

1. In a machine of the character described, a supply hopper equipped with feeding means arranged to discharge a regulated supply of comminuted material, a meshed conveyor belt arranged to transfer wafers laterally under said hopper, a vibrating screen between said supply hopper and conveyor belt arranged to receive the 35 material discharged from such hopper and sprinkle it upon the wafers on the belt, a collecting hopper arranged vertically beneath said screen including inclined sides converging downwardly and terminating in a transverse conveyor trough, and an elevator mechanism arranged to receive material from said trough and deliver it to said supply hopper.

2. In a machine of the character described, a meshed conveyor belt, supply and distributing means above said belt arranged to sprinkle comminuted material upon wafers supported upon said belt, blower mechanism including a nozzle extending transversely 50 across the machine adjacent said conveyor belt and having an adjustable jet orifice arranged to dislodge excess material from said wafers, and means for returning surplus and excess material passing through said belt to the source of supply.

3. In a machine of the character described, a meshed conveyor belt, supply and distributing means above said belt arranged to sprinkle comminuted material upon wafers supported upon said belt, blower 65

mechanism including a nozzle extending transversely across the machine adjacent said conveyor belt and having a cylindrical longitudinally-slotted member rotatably mounted in said nozzle and arranged to dislodge excess material from said wafers, and means for returning surplus and excess material passing through said belt to the source of supply.

4. In a machine of the character described, 70 a supply hopper for comminuted material extending transversely of the machine and having ends and sides, a pair of feed rollers arranged longitudinally of the hopper to form a bottom closure with a feed opening therebetween, a spiral distributing blade arranged above said feed rollers, means for supplying the comminuted material adjacent the inner end of said blade, and means for rotating said rollers and said distributing blade.

5. In a machine of the character described, 75 a supply hopper for comminuted material extending transversely of the machine and having ends and sides, a pair of feed rollers arranged longitudinally of the hopper to form a bottom closure with a feed opening therebetween, a spiral distributing means in said hopper arranged to spread the material longitudinally above said rollers, a meshed conveyor for conveying cakes laterally underneath said feed opening, means for returning surplus material passing through said meshed conveyor and discharging it into said hopper adjacent the inner end of said distributing blade, and means for rotating said rollers and said blade.

6. In a machine of the character described, 80 a supply hopper for comminuted material extending transversely of the machine and having ends and sides, a pair of feed rollers arranged longitudinally of the hopper to form a bottom closure with a feed opening therebetween, a spiral distributing blade arranged inside the hopper above said feed rollers and journaled in the hopper ends, means for supplying the comminuted material adjacent the inner end of said blade, and means adjacent one end of the hopper for rotating said rollers and said distributing blade including intermeshing gearing outside the plane of the hopper end on the shafts of said rollers and blade.

7. In a machine of the character described, 85 a supply hopper for comminuted material having at its bottom a pair of feed rollers arranged to be driven at the same peripheral speed and having cylindrical faces formed with longitudinal grooves, the grooves of the two rollers being angularly offset and the margins of the grooves of one roller being arranged to rotate into registration with the cylindrical faces of the opposite roller.

8. In a machine of the character described and having an endless belt for conveying wafers through the machine, means for driving said belt including a pair of small rollers engaged by the upper reach of the belt, one of said rollers being an idler roller and the other positively driven, a second idler roller, and a relatively large positively driven roller in a bight of the belt between said last mentioned idler roller and said small idler roller.

9. In a machine of the character de-

scribed, a conveyor belt arranged to support wafers, supply and distributing means above said belt arranged to sprinkle comminuted material upon wafers on said belt, blower mechanism including a nozzle extending transversely across the machine adjacent said conveyor belt and having an adjustable jet orifice arranged to dislodge surplus material from said wafers, and means for returning dislodged surplus material to the source of supply.

FERDINANDO G. SALERNO.
